UNITED STATES PATENT OFFICE.

SAMUEL K. SNAVELY, OF LITITZ, PENNSYLVANIA, ASSIGNOR TO J. R. BRICKER & CO., OF SAME PLACE.

DESIGN FOR A CIGAR.

SPECIFICATION forming part of Design No. 31,847, dated November 14, 1899.

Application filed October 19, 1899. Serial No. 734,130. Term of patent 7 years.

To all whom it may concern:

Be it known that I, SAMUEL K. SNAVELY, a citizen of the United States, residing at Lititz, in the county of Lancaster and State of Pennsylvania, have invented and produced a new and original Design for Cigars, of which the following is a specification, reference being had to the accompanying drawings, forming part thereof.

- 10 Figure 1 is a perspective view of a cigar, showing my new design; and Fig. 2 is a side view thereof.

As shown in the drawings, the leading or material feature of my design consists of the body A, the tuck B, and the concavo-convex neck D, connecting the body A and the tuck B, the parts being disposed or arranged as shown in the drawings. Beneath the convex

curve E, connecting the upper side of body A with neck D, there is a concave curve F in 20 the under side of the cigar..

It is apparent that this design is also applicable to cheroots.

Having described my invention, what I claim as new, and desire to secure by Letters 25 Patent, is—

The design for a cigar, as herein shown and described.

In testimony whereof I have signed my name to this specification, in the presence of 30 two subscribing witnesses, this 17th day of October, A. D. 1899.

SAMUEL K. SNAVELY.
